UNITED STATES PATENT OFFICE.

JOEL O. WILDER, JR., OF BERKELEY, CALIFORNIA.

DENTAL IMPRESSION DEVICE.

Application filed October 30, 1926. Serial No. 145,108.

This invention relates to improvements in dental impression devices and more particularly to compression means for holding and compressing a plastic composition for taking 5 dental impressions.

In the practice of dentistry, particularly in the mechanical technique, in the taking of impressions for the purpose of replacing teeth and replacing parts of teeth by means 10 of inlays, crowns, bridges and other mechanical dentures, it is important that a high degree of accuracy be maintained in taking these impressions, not only of the immediate tooth involved but also of surrounding dental 15 conditions for the guidance of the operator in accomplishing accurate replacement with perfect occlusions of the permanent tooth with the replacement.

Heretofore it has been the practice to introduce a lump of plastic compound between the jaws of the patient, having him bite down thereinto, thereby leaving an impression of the teeth involved. This method is crude and faulty in that, the plastic material 25 in flowing away from the bite is distorted and does not leave a true impression, with the possible exception of the occlusive portions of the teeth. Furthermore in removing the compound from the patient's mouth it is 30 very apt to become distorted in detaching it from the teeth to which it may adhere, or by the general handling by the operator. It has also been the practice where a small area was involved, such as, merely the occlusive surface 35 of one tooth, to surround the opposite tooth with a girdle of metal, having the impression compound therein and have the patient bite down thereinto. This likewise, is more or less of a make-shift method, resulting 40 in distorted or untrue impressions, and gives no impression of the adjacent teeth for accurate replacement as in bridge-work.

The principal object of this invention is to provide means that will mechanically hold 45 the mass of plastic impression material for first placement and subsequent handling and also to provide means for compressing the plastic laterally during the period or immediately following the bite of the patient 50 into the plastic mass before it hardens, the purpose being to perfect the lateral impression of the teeth involved so as to get a true impression and maintain the same. Other objects and advantages will appear as this 55 description progresses.

In this specification and the annexed

drawings the invention is illustrated in the form considered to be the best, but it is to be understood that the invention is not limited to such form because it may be embodied 60 in other forms, and it is also to be understood that in and by the claims following the description it is desired to cover the invention in whatsoever form it may be embodied.

In the accompanying one sheet of drawings, Figure 1 is a plan view looking down into a dental device constructed in accordance with this invention and applied to the lower mandible. Figure 2 is an end view of 65 the same.

In detail the construction illustrated in the drawings comprises the base plate 1, substantially oval in plan, having the rounded ends 2 and 3 and transversely concavo-convex as shown in Figure 2. The outer perimeter of the base plate is provided with a flange 4 to aid in holding the impression compound within the base plate. It is also provided with the convenient handle 5 extending outwardly from the end 3 of the 70 plate.

This base plate is provided with a transverse hole through its center to pass the stem 6. The outer end of this stem is shouldered to provide a rivet 7 for fixing the compression plate 8 on the end thereof. This compression plate is similar in contour and construction to the base plate 1, and is held in juxtaposition thereto by the stem 6. It is similarly transversely concavo-convex and 85 has the flange 9 around its perimeter for the purpose of retaining the plastic impression mass. These plates, 1 and 8, will vary more or less in contour and shape as they are made in various sizes to fit particular locations in 90 the mouth of the patient, and are appropriately shaped to meet the anatomical conditions at these various points without departing materially from the major characteristics of the plates shown in the drawings. 100 The opposite end of the stem 6 is flattened and pivoted at 10 to the toggle lever 11 that is pivoted at 12 in the stud 13 extending outward from the back of the base plate 1, adjacent to the end. The toggle lever 11 is 105 pivoted at 14 to the handle lever 15 that is pivoted in the stud 16 rising from the base plate at the opposite end. The handle lever is provided with a convenient handle 17 in juxtaposition to the handle 5. The toggle 110 action just described causes the compression plate 8 to advance toward the base plate 1

when the handles 5 and 17 are pinched between the thumb and fingers of the operator. The various parts of the device should be made of such material, and finished and shaped, to facilitate cleaning and sterilizing.

This invention is operated substantially as follows: The operator takes a mass of plaster, wax or other plastic impression compound and forces it between the plates 1 and 8, which are forced apart thereby until the handles 5 and 17 separate as shown in Figure 1, the impression compound surrounding the stem 6 and fitting within the flanges 4 and 9. The device is then inserted between the jaws of the patient with the impression compound between the teeth of the upper and lower jaws, the stem 6 being adjusted to pass into the gap in the upper or lower jaw, as the case may be, where the tooth to be replaced is missing, see Figure 1. The patient is then instructed to bite into the impression compound until his teeth meet, in the usual manner. The impression compound displaced by the entrance of the teeth thereinto flows out past the plates 1 and 8, forming a cup like depression surrounding the various teeth embedded in the impression compound. After the patient has bitten into the impression compound the required distance and moved his jaws to insure a perfect occlusion between his upper and lower teeth, he is instructed to hold the bite hard in position while the operator pinches the handles 5 and 17 between his fingers, which shortens 35 the distance between the base plate 1 and the compression plate 8, compressing the

compound therebetween laterally against the sides of the teeth embedded therein, perfecting a lateral impression of the teeth and the interstices between. While the operator holds the handles 5 and 17 the patient is instructed to withdraw his teeth from the impression compound which leaves a perfect impression of the occlusion and also of the sides of the various teeth below the line of the "bell" and above the occlusive surfaces. The device is then removed from the mouth of the patient, the excessive impression compound trimmed off and the operator has a perfect mold of the teeth involved in the future mechanical operations, and he proceeds with the usual mechanical technique indicated by the conditions to be met.

Having thus described this invention what I claim and desire to secure by Letters Patent is:

1. A dental device comprising a base plate; a stem passing through said base plate; a compression plate fixed upon said stem; a toggle mounted upon said base plate and engaging said stem.

2. A dental device comprising a base plate; a stem passing through said base plate; a compression plate fixed upon said stem; a toggle lever pivoted to said base plate and said stem and a handle lever pivoted to said base plate and said toggle lever.

In testimony whereof I have hereunto affixed my signature.

JOEL O. WILDER, JR.
